WARM AIR FURNACE

Rudolph W. Menk, Joliet, Ill.

Application November 16, 1935, Serial No. 50,191

3 Claims. (Cl. 126—99)

My invention relates to heating appliances, and has more specific reference to warm or hot air furnaces for the heating of houses, or other apartments.

One of the principal objects of my invention is to provide a furnace that is fabricated almost entirely of sheet metal plates that are joined together preferably by welding to provide tightly sealed joints that effectively prevent escape 10 of air and gas from the structure. When constructed in the aforesaid manner the cost of production is substantially reduced, as is also the weight of the furnace, and by means of the novel construction and arrangement of the component parts the efficiency of the heating apparatus is considerably increased.

Other objects of my invention are to provide a furnace that is novel in construction; is dependable in use; is capable of being readily assembled 20 when being manufactured, and also when being installed or erected in a house; and is effective in performing the functions for which it is designed. Further objects and advantages of my furnace will be obvious to persons skilled in the 25 art after the construction and operation thereof is understood from the following detailed description.

I prefer to accomplish all of the objects of my invention, and to practice the same in substantially the manner hereinafter fully described and as more particularly pointed out in the appended claims. In connection with this description reference is made to the accompanying drawings forming a part of this specification.

35 In the drawings:—

Figure 1 is a vertical axial section of my heating furnace, the view being made on the plane of line 1—1 of Figure 2.

Figure 2 an elevation looking at the rear of the 10 furnace body, the outer casing being shown in dotted lines.

Figure 3 is a horizontal section taken on line 3—3 of Figure 1, looking down in the direction of the arrows.

Figure 4 is a vertical section on line 4—4 of Figure 1, looking towards the front of the furnace in the direction of the arrows.

Figure 5 is a detail view showing the manner of installing or removing the fire-brick.

0 The drawings, which are more or less schematic, are for the purpose of disclosing a typical or preferred form in which my furnace may be constructed; and in said drawings like reference characters identify like parts appearing in 5 the different views.

The body of the furnace is preferably entirely surrounded or enclosed within an outer shell or casing 5 which is made of the usual gauge of sheet-metal, and in the present instance the casing is conveniently made rectangular in shape 5 with rounded corners. There is a tapered bonnet at the top of the casing which is provided with discharge openings for egress of the heated air to the distributor pipes (not shown) and at the rear, near the bottom of the casing there is an 10 inlet opening that is connected to a return-air conduit or pipe 6. At the front of the casing there is a panel 7 that is provided with a feed opening and door 8 and an ash-pit opening and door 9, both of which doors are provided with 15 air or draft control dampers.

The furnace body within the casing 5 is a cylindric unitary structure formed from plates of sheet-metal of much heavier gauge than the gauge of the sheet-metal used in the casing, and this body is of simple and novel construction. The main portion of this body is a sheet metal cylinder or shell 10 standing upright to dispose its axis vertical and it is supported above and spaced from the floor by L-shaped feet 11 that 15 are welded to the outer face of the body or shell.

The upper and lower ends of the cylindric body 10 are closed by outwardly bulged or bellied plates 12 and 13 respectively so that a drum-shaped furnace body is provided having a dome-shaped top and an inverted dome-shaped bottom. A feed opening is made in the front wall of the cylindric body 10 alining with the feed opening and door 8 in the panel and rectangular shaped horizontal and vertical walls connect the 30 corresponding edges of these alined openings to provide a suitable passageway 14 from outside the casing 5 to the interior of the body where the combustion chamber is located. Another opening is made in the lower portion of the cylindric 35 body 10 alining with the ash-pit opening and door 9 in the panel and rectangular shaped horizontal and vertical walls 15 connect the corresponding edges of these openings to provide a 40 suitable passageway leading to the interior of the 45 ash-pit.

The fuel grates 16 of the rocker type extend across the lower portion of the body 10 in a horizontal plane above the top of the door 9 and divide the interior of said body into an upper 50 combustion chamber 17 and a lower ash-pit 18. The interior surface of that portion of the combustion chamber in which the fuel is placed and burned is faced with fire-bricks 19 that are supported upon an annular shelf 20 extending 55

inwardly around the lower portion of the combustion chamber just above the plane of the grates, and said fire-brick are secured in position by metal clamps 19^a that are bolted to the 5 inside faces of the vertical plates forming the fuel passage-way 14.

In order to rock or vibrate the grates a horizontally disposed shaker bar 21 extends from outside the casing into the ash-pit 18 where it is 10 suitably connected to said grates, while the opposite or outer end of said shaker bar is pivotally connected to a vertically disposed operating handle 22. The portion of the shaker bar between the handle and the ash-pit is enclosed 15 within a housing π having guide slots at each end on which said bar is reciprocably disposed. This arrangement prevents egress of dust and ashes out of the ash-pit during the operation of shaking the grates.

20 At the top of the combustion chamber the body or shell 10 is provided with a horizontally elongated opening 23 that extends in an annular direction slightly less than half-way around the rear segment of the body. In height, 25 this opening 23 extends from just above the top of the fire-brick 19 up to near the top of the cylindric metal plate forming the body or shell. A row of fire-bricks 24, having one or more openings 25 therein, are placed in the opening 30 23. The cubical dimensions as well as the surface areas of these fire-bricks are greater than the corresponding dimensions of the adjacent portions of the metal wall. A heat-retaining body results from this arrangement in which 35 the temperature is readily built up and retained even after the bed of fuel in the furnace has died down, and since said heat-retaining body has greater surface area and bulk than the normal area and bulk of the much thinner metal 40 plate of the furnace wall the gases in passing this heat-retainer body will maintain their temperatures and combustion will continue and will not be retarded as the gases travel in their movement out of said chamber 17. In addition to 45 the foregoing, the fire-bricks afford protection to the edges of the metal wall which they overlap at the opening, and they restrict the size of the outlet opening and divide the stream of combustion gases passing out of the chamber, so that 50 when combustion has been retarded and the fire dies down this fire-brick heat-retaining body will continue to radiate heat. For the purpose of permitting the ready installation or removal 55 of these fire-bricks their top and bottom edges are provided with channels or grooves 26 and 27 respectively, the former or top grooves being deeper than those in the latter or bottom edges of the bricks.

60 Thus, the top of a brick is first engaged with the upper margin of the opening 23 and moved upward until the adjacent edge of the metal plate reaches the bottom of the groove 26, after 65 which the lower edge of the brick may be moved into the opening in order to align the bottom groove 27 with the lower edge of the opening and then lowered to its proper position. This is detailed in Figure 5. The vertical edges of 70 the fire-bricks are provided with rabbets 28 which permits overlapping of the edges of the adjacent bricks and also permits the end edges of the end-bricks to overlap the vertical edges of the opening 23. The egress opening or openings 25 are 75 made by molding the adjacent bricks in somewhat of a U-shape which is readily done by

forming rectangular cut-out portions in the meeting edge portions of the respective bricks.

A radiator of novel construction is located at the rear of the body or shell 10 and consists of a box-like structure having vertical side walls 29 5 that extend rearwardly tangent to the sides of the cylindric shell, and a vertical rear wall 30 connects the rear edges of the side walls. These walls are rectangular metal plates that are welded to each other and to the outer surface of the 10 shell so that said radiator projects rearwardly from the upper portion of the body or shell as seen in Figures 1 and 3. At or adjacent its lower edge, the rear wall 30 is provided with a smoke outlet to which a sheet-metal stub or 15 sleeve 31 is welded.

The top and bottom walls 32 and 33, respectively, of the radiator consist of substantially rectangular horizontally disposed sheet-metal plates that are united by welding to the respective edges of the vertical walls 29 and 30, and the forward portions of these top and bottom walls have segmental or substantially semi-circular cut-out portions so that said edges will be shaped to fit against and be welded to the 25 outer surface of the body 10. It will be seen the upper segment of the smoke outlet is spaced a substantial distance below the horizontal plane of the lower edge of the opening or openings 25 30 in the fire-brick communicating into the combustion chamber, so that the hot products of combustion, after leaving the body or shell 10, must travel in a downward direction in the radiator before said products can escape to the 35 chimney or other discharge flue.

In order to further retard movement of the hot products of combustion in their travel from the combustion chamber 17 to the chimney, an inverted V-shaped baffle 34 is installed within the radiator. This baffle preferably consists of a sheet metal plate that is bent intermediate its side edges to provide two inclined members 34^a and 34^b that slope downwardly from the bend which provides the apex 34^c of the baffle. By 45 reference to Figures 1 and 2 it will be seen that the baffle is positioned so that the apex 34^c thereof is above the smoke outlet and sleeve 41, and the lower edges of the inclined members 34^a and 34^b terminate at about the horizontal plane of 50 the axis of the smoke-outlet and also are spaced from the vertical side walls 29 of the radiator so that elongated narrow passageways 35 are provided at the opposite side edges of the baffle. 55

The products of combustion upon entering the 60 radiator are divided by the baffle, being compelled thereby to move towards the side walls 29 of the radiator and then practically reverse their direction of movement in passing around the opposite edges of the baffle before they can reach the smoke 65 outlet. These circuitous paths tend to retard movement of the hot products of combustion with the result that said products remain a longer period of time in this novel radiator than in the case in radiators of ordinary construction. Another feature is that the fire-bricks 24 with their spaced openings to divide the hot products of combustion perform the function of a heat-retainer body and assist in maintaining a hot temperature in the radiator. Also it will be apparent 70 that the furnace body, including the radiator, being fabricated from sheet-metal plates welded together, will become heated more rapidly than cast metal structures and the air which is circulated inside the casing 5 around these elements 75

will become heated in less time than in other and similar types of warm-air furnaces.

What I claim is:

1. A device of the kind described embodying furnace walls providing a combustion chamber, one of said walls having an opening, a radiator communicating with the combustion chamber through said opening, and fire-bricks mounted in and surrounding said opening whereby to provide a heat-retainer body, the top and bottom edges of said bricks provided with seats receiving the wall edges at said opening whereby to mount said bricks and protect the edges of said opening.

2. A warm-air furnace embodying vertical and horizontal sheet-metal walls providing a combustion chamber, one of said walls having an opening, a sheet-metal radiator on the exterior of said walls and communicating with the combustion chamber through said opening, and fire-bricks mounted in said opening and surrounding the

sheet-metal wall at the edges thereof, all of said bricks provided with edge seats to receive the edges of the wall at said opening whereby to mount said bricks and protect said wall edges, and certain of said bricks having a U-shaped body whereby to constrict the area of said opening.

3. A warm-air furnace embodying walls providing a combustion chamber having an outlet opening, a radiator communicating with said chamber through said opening, and fire-bricks mounted in and surrounding said opening, said bricks being of greater thickness than the wall defining said opening whereby to provide a heat-retainer body about said opening, certain edges of said bricks having longitudinal grooves receiving the edges of said wall at said opening whereby to protect said edges and afford means for mounting said bricks in said opening.
